UNITED STATES PATENT OFFICE.

BRUNSON S. McCUTCHEON, OF NORTH PLAINFIELD, NEW JERSEY.

WRINGER FRAME.

Application filed June 21, 1930. Serial No. 390,423.

To all whom it may concern:

Be it known that BRUNSON S. McCUTCHEON, a citizen of the United States of America, residing at North Plainfield, in the 5 county of Somerset and State of New Jersey, has invented certain new and useful Improvements in Wringer Frames, of which the following is a specification.

My invention relates generally to clothes 10 wringers and has for its principal object to provide a pressed steel wringer frame made of duplicate or identical and consequently interchangeable sections, members and parts.

Other and further objects and advantages 15 will be in part, apparent and in part explained as the specification is proceeded with.

In the accompanying drawings forming a part of this specification:

20 Figure 1 is a side elevation of a roller wringer-frame constructed in accordance with my invention:

Figure 2 is a top plan view of the same;

25 Figure 3 is a section on the line 3—3 of Figure 1; looking in the direction of the arrows;

Figure 4 is a section on the line 4—4 of Figure 1; looking in the direction of the arrows;

30 Figure 5 is a detail view of the clamping bolts for the frame sections and

Figure 6 is a perspective view of one of the drip guards or shields detached.

Referring more particularly to the drawings wherein like reference numerals designate corresponding parts, 1 denotes generally a wringer-frame for power wringers formed in duplicate identical sections, or members 2 and 3 of sheet metal, each section 35 being in a continuous or single piece and pressed into the shape illustrated by means of suitable dies (not shown) and preferably in a single operation. As clearly shown each frame section comprises upper and lower 40 horizontally and parallelly disposed top and bottom members 30 and 31 and vertically and parallelly disposed side members or portions 32 and 33 each of which being substantially U-shaped in cross section form an end-

45 less tubular wringer frame when the sections or members 2 and 3 are placed together edge to edge. Each frame section has a vertical rib or guide 4, quite near each vertical edge formed preferably by inwardly depressing 50 or sinking into a wall thereof, oblong 55 formations, the resultant projections or ribs

extending from the inner surface of said wall as seen particularly in Figure 3. As also shown in the same figure, bearing blocks 5 are positioned within the wringer-frame 60 for the support of the ends of the lower and upper wringer rollers, the lower roll, designated as 6, being indicated in dotted lines, said bearing blocks being longitudinally recessed, as indicated at 7 in said lower bearing block, to receive the guides 4 of the wringer frame. It will thus be seen that the bearing blocks are free to slide vertically but locked against lateral movement. Each frame section has coincident orifices 8 there- 65 in, to receive nut equipped bolts 9 housed within spacing sleeves 10 intermediate the frame sections, the two lowermost of said bolts serving to support the bearing block for the lower wringer roll. The driving 70 gearing 20 for the rolls as indicated in a general way in dotted lines in Figure 3, is suitably mounted in the vertical portions of the frame.

Suitably interconnected or interlapped 75 with the frame sections, as at 11, 12 are what may be termed water shed cups 13, adapted to receive the water drip from the rolls and deflect the same onto the water board (not shown). These cups are formed 80 with inwardly bent portions 12 which are adapted to interlock with the edges 11 of the cut away portions 35 of the vertically disposed side members of the frame, as shown in Figures 3 and 4. Along the bisect- 85 ing line of the wringer frame, the sections or members 2, 3 thereof are suitably extended upwardly as at 14, the resultant upward-extensions having a tubular formation to 90 suitably provide for the reception of the usual compression screw and release mechanism (not shown). The upward extensions 14 are suitably bolted together as shown at 15.

Formed integral with each section of the 100 wringer-frame is a pressed-out leaf like member 16 preferably slightly inclined downwardly for facilitating the passing of the articles or clothes to the wringer-rollers and conveniently forming a rest for said 105 articles in transit to said rollers and therefrom. The leaf-like member proper 16 is offset from the body portion of the wringer-frame section as seen particularly in Figure 4, the connection therebetween being in the 110 form of outstanding arms 16^a all, of course, being in a single piece. Said leaf-like mem-

bers 16 are formed in their vertical portions with outwardly pressed eye or loop-forming portions 17.

In practice the wringer frame and parts 5 are assembled as follows: One half of the frame is laid on its side, and the various parts placed therein or attached thereto, similar to building up a puzzle structure. The two frame members are then placed in 10 juxtaposed position and clamped together by means of bolts 9.

From the foregoing it will be seen that my wringer frame is light and simple, can be readily constructed and accordingly cheaply 15 manufactured. Furthermore that the wringer rolls and shafts and bearing blocks therefor, also the compression screw and spring therefor and release mechanism are

held in place without the aid of screws, bolts, rivets or the like. It will also be noted that 20 the deflectors or guards 13 are likewise held in place without the use of bolts or screws.

What I claim is:

A wringer-frame formed in sections adaptable conjointly to form a tubular frame 25 structure, each frame-section having pressed therein a leaf like member extending transversely with respect to the vertical edges of said section and being outwardly bent and slightly downwardly inclined, said leaf 30 member proper being offset from, and having arm-like connections with said frame-section, all in one piece.

In testimony whereof I affix my signature.

BRUNSON S. McCUTCHEN.
